UNITED STATES PATENT OFFICE.

NICHOLAS RAPPLEYEA AND LEO STEIN, OF ROCHESTER, NEW YORK.

DESIGN FOR A COFFIN-PEDESTAL.

SPECIFICATION forming part of Design No. 13,017, dated June 27, 1882.

Application filed May 8, 1882. Term of patent 7 years.

To all whom it may concern:

Be it known that we, NICHOLAS RAPPLEYEA and LEO STEIN, of Rochester, Monroe County, New York, have invented and produced a new and original Design for Coffin-Pedestals; and we do hereby declare that the following is a full, clear, and exact description of the same, references being had to the accompanying photographic illustration, which shows a perspective view of the device.

This design relates to a pedestal or support for coffins and burial caskets; and it consists of a molded or beaded column having a center covering of tufted work, thereby adding to the ornamental appearance of the column.

In the drawing, *a* indicates the plinth; *b*, the moldings at the bottom of the column; *c* is the abacus, *d* the moldings at the top of the column, and *f* is the cylindrical center of the column. *g* is a covering of tufted work placed around the cylindrical portion, and *h h* are twisted cords at top and bottom of the

tufted work. The tufted work is cylindrical in outline, but presents an indented surface at regular intervals over the whole exterior, as shown. The pedestal in the form of a molded or beaded column and having its central portion covered by tufted work, as described, presents a highly ornamental and beautiful appearance.

What we claim as new is—

The design for a coffin-pedestal, consisting of a molded or beaded column having a covering of tufted work on its central cylindrical portion, as herein shown and described.

In witness whereof we have hereunto signed our names in the presence of two subscribing witnesses.

NICHOLAS RAPPLEYEA,
LEO STEIN.
